US00D894754S

(12) **United States Design Patent** (10) **Patent No.:** **US D894,754 S**
Hesse (45) **Date of Patent:** **** Sep. 1, 2020**

(54) **PACKAGING**

(71) Applicant: **Corr-Jensen Inc.**, New York, NY (US)

(72) Inventor: **Matthew Hesse**, New York, NY (US)

(73) Assignee: **Corr-Jensen Inc.**, Denver, CO (US)

(**) Term: **15 Years**

(21) Appl. No.: **29/601,263**

(22) Filed: **Apr. 20, 2017**

(51) LOC (12) Cl. **09-01**

(52) U.S. Cl.

USPC **D9/715**; D9/558; D9/519

(58) **Field of Classification Search**

USPC D9/414, 428, 500, 516, 519, 520, 715,
D9/719

CPC B65D 2543/00092; B65D 83/04

See application file for complete search history.

(57) **CLAIM**

The ornamental design for a packaging, as shown and described.

DESCRIPTION

FIG. 1 is a front perspective view of packaging; FIG. 2 is a front view of the packaging shown in FIG. 1; FIG. 3 is a top view of the packaging shown in FIG. 1; and, FIG. 4 is a bottom view of the packaging shown in FIG. 1. The broken lines and areas within the broken lines in FIG. 4 depict portions of the packaging that form no part of the claimed design. The remaining broken lines shown depict portions of the packaging that form no part of the claimed design.

1 Claim, 4 Drawing Sheets
